UNITED STATES PATENT OFFICE.

WILLIAM M. CLEMANS, OF WHEELING, WEST VIRGINIA.

REFRIGERATOR.

Application filed February 14, 1921, Serial No. 444,957. Renewed June 25, 1923.

To all whom it may concern:

Be it known that I, WILLIAM M. CLEMANS, a citizen of the United States of America, and resident of Wheeling, county of Ohio, and State of West Virginia, have invented certain new and useful Improvements in Refrigerators, of which the following is a specification.

This invention relates broadly to refrigerators, and, while it is directed primarily to storage refrigerators of the mechanically cooled type commonly employed in mercantile houses, such as packing houses, butcher shops, milk depots and the like, it is also intended to embrace refrigerators of small size and of ice-cooled type.

The primary object of the invention is to provide a refrigerator having improved and adjustable means whereby a greatly accelerated circulation of air may be maintained therein for lowering the temperature and, consequently, for increasing the efficiency for effecting refrigeration.

A further object is to provide a deck and baffle construction for refrigerators, which affords adjustable means whereby effective regulation of the circulating air drafts may be readily controlled.

With these and other objects in view, the invention resides in the features of construction, arrangement of parts and combinations of elements which will hereinafter be fully described, reference being had to the accompanying drawings, in which—

Figure 1 is a transverse vertical section of a mechanically cooled refrigerator of one of the larger types, embodying my invention;

Figure 2 is a fragmentary section on line 2—2, Fig. 1;

Figure 3 is a vertical section of a refrigerator of a large type embodying a modified form of the invention;

Figure 4 is a similar view of a refrigerator of smaller or domestic size, showing another modification; and—

Figure 5 is a similar view of a refrigerator of the low box, or show-case, type, showing a further modification of the invention.

Referring first to the structure shown in Figs. 1 and 2 of the drawings, 1 designates the top and 2 the opposite side walls of a refrigerator body or casing. Mounted within said casing at an appropriate height are longitudinally-extending companion coil-decks disposed horizontally, or approximate-

ly so, the same being herein indicated generally by numerals 3. Said decks are preferably of equal dimensions and preferably occupy a common horizontal plane, although they may be slightly inclined downward in inward directions. Each deck has its outer edge located at a suitably spaced distance from the adjacent side wall 2 of the casing, as will be explained hereinafter. The width of said decks is such that their inner edges are separated by a space or passage having a width affording a capacity at least equal to that which it is predetermined shall be adequate to freely conduct the maximum volume of air that may at any time be required thereof.

Each coil deck 3 comprises a lower platform 3' and an upper platform 3'', the latter parallel with and spaced from the former to provide an intermediate horizontal slideway 4 in which is received the outer lateral edge portion of a panel 5. Said panel is slidably disposed in said slideway and is designed for adjustment relative to the opposite deck to any extent which may in practice be required.

Rising vertically from the outer edge portion of each coil deck 3 is a bridge-wall of the general character commonly termed a baffle-board, the same being herein generally designated by the numeral 6. Each of said baffle-boards comprises two upright parallel bridge members 6' and 6'' disposed in spaced relation to provide an intermediate vertical slideway 7 similar to the slideways 4 hereinbefore described. The inner bridge member 6'' rises from the outer edge of the platform 3'', while the outer member 6' rises from the outer edge of the platform 3', as shown, said outer member thus being spaced from the adjacent casing wall 2 to form an intermediate passage 8 through which air in maximum volume may course upward from the storage chamber 9 located beneath the coil decks.

The baffle-boards 6 terminate at a distance from the top 1 to provide an intermediate space or passage having a capacity at least equal to the maximum required for the passage of air thereover. Vertically slidable in each of the slideways 7 of said baffle-boards and projecting upward therefrom is a panel or gate 10 which is adapted for adjustment relative to the top 1 somewhat in the manner of a damper to restrict more or less the capacity of the intermediate

space or passage 11 as may be requisite for regulation of air circulation through said passage.

While the gates 10 are herein shown as suspended by cords or cables 12 passed over suitably arranged pulleys 13, it is obvious that various other means for effecting adjustment thereof may be employed, as, for example, a rack and pinion device similar to that herein shown in connection with each of the slide panels 5. The said rack and pinion device provided for shifting each panel 5 comprises a pinion 14 carried by a longitudinally disposed shaft 15 mounted in suitable bearings, as bearing brackets 16 carried by the lower platform 3' of the coil deck 3. Said pinion is disposed in operative relation to a rack bar 17 which is carried on the under side of the adjacent slide panel 5 in countersunk relation to the latter.

Each of the various platforms, bridge members, slide panels and gates is preferably composed of a plurality of superposed thicknesses or layers of material, of which an intermediate layer is preferably cork or other suitable insulating material or composition, designed to render said parts not readily conductive of heat or cold.

In practice, air cooled by contact with, or through proximity to, the cooling coils 18 located in the cooling chamber 19 over the coil decks 3 descends into the storage chamber 9 through the passage 20 between said coil decks, or rather between the inner edges of the slide panels 5, the latter being adjusted relatively to suitably regulate the width and, consequently, the capacity of said passage for conducting air. Warm currents of air in the storage chamber, displaced by the descending cold air, rises adjacent to the side walls 2 of the refrigerator casing and passes upward through the opposite passages 8 and thence over the bridges or baffles 6 to the cooling chamber, the gates 10 being adjusted to restrict the capacity of the passages 11 to a greater or less extent as may be required for circulation of the character desired.

In the modification shown in Fig. 3, the arrangement of the decks and baffles is reversed, thereby creating a reversal of the direction of the circulation, the baffles 6^a rising from the inner end instead of the outer ends of the decks 3^a and having the slide panels 5^a adjustable with respect to the side walls 2.

In Fig. 4, which illustrates a refrigerator casing of a relatively small size, such as those commonly employed in small stores and residences, a single coil deck and baffle is disclosed, the arrangement being the same as that shown in Fig. 1, except that the slide panel 5^b is adjustable with respect to the wall opposite to that adjacent to which the baffle 6^b is located.

The refrigerator depicted in Fig. 5 is of low counter or show-case type, having a series of cooling pipes 21 located in vertically aligned relation adjacent to one of the side walls thereof. Located in front of said pipes is a vertically disposed baffle board 6^c having panels 5^c slidably mounted in both the upper and lower edges thereof and adjustable, respectively, with respect to the top and bottom of the case. 75

From the foregoing it will be manifest that, through adjustment of the slide panels and gates, the circulation of air may be positively controlled for creating and maintaining a relatively lower temperature than is possible where such control is lacking. Further, the described structure provides for the regulation of the circulation in such manner that the objectionable, but common, sweating of objects within the storage chamber resulting from condensation of moisture may be effectually eliminated. 80 85

What is claimed is—

1. In a refrigerator, a casing, companion decks partially separating the interior of the casing into an upper cooling chamber and a lower storage chamber, said decks being relatively spaced to provide an intermediate air circulation passage between said chambers, said decks being also spaced from the opposite side walls of said casing to provide side passages, bridges superposed on said decks and spaced from the top of the casing to form intermediate passages, panels slidably disposed within said decks and adapted for movement toward and away from each other for closing or partially closing said intermediate passage, and panels slidably disposed within said bridges and adapted for movement toward and away from the top of said casing for closing or partially closing said intervening passages. 90 95 100

2. In a refrigerator, a casing, companion decks partially separating the interior of the casing into an upper cooling chamber and a lower storage chamber, said decks being relatively spaced to provide an intermediate air circulation passage between said chambers, said decks being also spaced from the opposite side walls of said casing to provide side passages, bridges superposed on said decks and spaced from the top of the casing to form intermediate passages, panels slidably disposed within said decks and adapted for movement toward and away from each other for closing or partially closing said intermediate passage, means slidably disposed within said bridges and adapted for movement toward and away from the top of said casing for closing or partially closing said intervening passages, and means whereby said panels may be manually adjusted from the exterior of the refrigerator. 110 115 120 125 130

3. In a refrigerator, a casing, companion

- decks partially separating the interior of the casing into an upper cooling chamber and a lower storage chamber, said decks being relatively spaced to provide an intermediate air circulation passage between said chambers, said decks being also spaced from the opposite side walls of said casing to provide side passages, each of said decks comprising an upper and a lower platform with an intermediate slideway, substantially vertical bridges superposed upon said decks and having their upper edges spaced from the top of the casing to form intermediate passages, said bridges comprising parallel walls with intermediate slideways, and panels slidably disposed within each of said slideways.
4. In a refrigerator, a casing, companion decks partially separating the interior of the casing into an upper cooling chamber and a lower storage chamber, said decks being relatively spaced to provide an intermediate air circulation passage between said chambers, said decks being also spaced from the opposite side walls of said casing to provide side passages, each of said decks comprising an upper and a lower platform with an intermediate slideway, substantially vertical bridges superposed upon said decks and having their upper edges spaced from the top of the casing to form intermediate slideways, panels slidably disposed within
- each of said slideways and adapted for movement across the adjacent passages for totally or partially closing the latter, and means whereby said panels may be manually adjusted from the exterior of the refrigerator.
5. A refrigerator comprising an outer casing, means disposed within said casing separating the interior thereof into a lower storage and an upper cooling chamber, said means comprising L-shaped members having their vertical portions spaced both from the side walls and from the top wall of said outer casing to form intermediate air-circulation passages, the horizontal portions of said members extending inwardly toward, but terminating short of each other to provide an intermediate centrally located air-circulation passage, each of said members consisting of parallel walls with an intermediate slideway therebetween, panels slidably disposed within said slideways and adapted for movement toward and away from closing relation to said air circulation passages, and means manually operable from the exterior of said outer casing for adjusting said panels.
- In testimony whereof, I affix my signature in presence of a subscribing witness.
